UNITED STATES PATENT OFFICE

2,080,089

GRINDING APPARATUS

Engelbert Mühlbacher, Los Angeles, Calif.

Application March 17, 1934, Serial No. 716,082

6 Claims. (Cl. 51—109)

This invention relates to devices used for finishing and refinishing rounded surfaces, such as on crank-pins and cams.

One of the objects of this invention is to maintain the approximate position of the grinding wheel by cooperating guiding means contacting with a surface in pairing relation to the surface upon which the grinding wheel is operating.

Another object is to provide a simplified arrangement for changing from one crank-pin to another or from one cam to another on the same shaft.

Another object is to provide for accurate adjustments of the grinding wheel, making the apparatus economic and efficient.

Other objects will appear from the following description and appended claims as well as from the accompanying drawings, in which—

Fig. 1 is a front elevation of a grinding apparatus designed to operate according to this invention.

Fig. 2 is a fragmentary top plan view of the apparatus illustrated in Fig. 1.

Fig. 3 is a fragmentary longitudinal mid-sectional view of one of the main operating shafts.

Fig. 4 is a fragmentary cross section on line 4—4 of Fig. 1, showing the grinding mechanisms in end-elevation.

Fig. 5 is a fragmentary cross section on line 5—5 of Fig. 1, showing the control or guiding mechanisms in end-elevation.

Fig. 6 is a fragmentary cross section similar to the illustrations of Figs. 4 and 5, in this case showing a slightly modified form particularly adapted for use on cam-shafts.

Though the principal mechanisms can easily be applied to any common lathe or similar machine tool; as illustrated, however, the whole apparatus is arranged on a special frame structure, consisting in the main parts of the bed or central portion 11, the leg-portions 12 and 13, and the head-portions 14 and 15, indicated in Fig. 1.

From a motor, not shown in the drawings, in the leg-portion 12, a belt 16 transmits the motion to head-pulleys 17, by means of which a crank-shaft 18 may be rotated between points 19 of the head-portions 14 and 15.

If the crank-pins of a crank-shaft are to be finished or refined, the main portions of the crank-shaft are naturally well centered between such points 19, referred to above, and the different crank-pins of the crank-shaft maintain a certain relation to the central axis around which the shaft rotates.

With especially long shafts any customary cen-

tering supports, such as roughly outlined at 20, may be applied at any suitable or required place of the shaft, not in the least to interfere with the mechanisms of this apparatus.

The actuating or controlling attachment, illustrated in Fig. 5, is of a type to be applied to one of a pair of crank-pins, to cooperate with the grinding attachment illustrated in Fig. 4.

The attachments of the type of Figs. 4 and 5 depend for their proper cooperation upon the two control-shafts 21 and 22, extending throughout the whole length of the apparatus in front of the main frame structure, as more clearly illustrated in Fig. 2; in Figs. 4 and 5 the shafts 21 and 22 appearing alone, in cross-section, while the main frame structure is left off.

Any movement of the crank-pin, indicated in Fig. 5 at 23a of the crank 18, indicated in Figs. 1 and 2, is transmitted to the control-shafts 21 and 22 by means of the control attachment or mechanisms illustrated in Fig. 5; and the movement received by the control-shafts 21 and 22 is transmitted to the grinding attachment or mechanisms illustrated in Fig. 4.

The control mechanisms include therefore a control-arm 24 provided with an adjustable end, designed to suitably engage the crank-pin 23a by means of the contact-members 25 and 26, firmly provided on the arm 24, and another contact-member 27 provided on the adjustable clamp 28, whereby a suitable firm journal-connection can be provided for the arm 24 with the crank-pin 23a, adjustable to suit different crank-pins.

The opposite end of the arm 24 is pivotally connected at 29 to the lever 30, the lever in turn being removably mounted on the control-shaft 21, the hinge-connection at 31 and the clamping connection at 32 serving for adjustments of the lever with respect to the control-shaft 21.

A link 33, at one end pivotally connected at 34 to the arm 24, and at the opposite end pivotally connected at 35 to a second lever 36, which in turn is adjustably mounted on the control-shaft 22, serves to transmit motions of the crank-pin 23a to the control-shaft 22.

From the illustration of Fig. 5, and also with reference to the illustrations in Figs. 1 and 2, it will be understood that any rotating of the shaft 18 between the points 19, and thereby any swinging movements of the crank-pin 23a, results in oscillatory turning movements of both of the control-shafts 21 and 22.

These oscillatory turning movements are utilized for the proper operation of the grinding mechanisms illustrated in Fig. 4.

In internal combustion engines, modern crank-shafts customarily have crank-pins in pairing relation, making it possible that the control-mechanisms can be applied to one of the pairing crank-pins of a shaft, as at A, while the grinding mechanisms are applied to another of the pairing crank-pins of the same shaft, as at B, in Figs. 1 and 2.

Under this consideration, it must be understood that the different levers and arms and connections of the control-mechanisms of Fig. 5 as well as of the grinding-mechanisms can be so designed that the grinding-wheel 37 is just in a position to always follow the crank-pin 23_b according to the pairing crank-pins 23_a position, controlling the movements of the control-mechanisms, whereby the grinding-mechanisms are so maintained as to bring the grinding-wheel to the proper relation to the crank-pin 23_b operated upon by the grinding-mechanisms.

It may be said that the position of the grinding mechanisms is only approximately following the crank-pin 23_b, but that is sufficient, and that is exactly as it is desired.

For the sake of assuring accurate movements in the grinding mechanisms with respect to the particular pin, or cam, or surface, distinct adjustments are provided directly on the grinding mechanisms. The link 33_a is provided with an adjustment 38 whereby the contact-end 39 can be varied with respect to the crank-pin 23_b, for direct or positive contact as well as for spacing relation.

Regardless, however, of whether the contacting end 39 is used as a direct guiding means for the grinding-mechanisms, or not, a separate adjusting mechanism, indicated at 40, serves to bring the grinding-wheel 37 into operative position with respect to the crank-pin 23_b.

Assuming the arm 24_a is following closely the movements of the arm 24 of the control-mechanisms of Fig. 5, and also assuming that levers 36_a and 30_a of the grinding mechanisms are rather accurate duplicates of the levers 36 and 30 of the control-mechanisms of Fig. 5, a base 41 with a balancing weight 42 is provided mounted on the pivot 29_a adjustable by the adjustment 40 so as to vary the position of the grinding-wheel 37 nevertheless.

This arrangement makes it possible that the grinding wheel can be adjusted to a position to assure any desired accurateness.

Adjusting the arm 24_a so as to contact the end 39 with the crank-pin 23_b, to be operated upon, the adjustment 40 can be controlled so that the space between the contacting end 39 and the grinding wheel 37 is just the desired distance equaling the thickness of the crank-pin wanted in the finished pin or refinished pin.

The grinding mechanisms must then be said to be held approximately, though really rather accurately, to follow the crank-pin 23_b, according to the movements of the crank-pin 23_a, by means of the control-mechanisms, and, in addition, be guided by the adjustable guiding facilities directly on the grinding mechanisms.

The upper parts 43 of the grinding mechanisms are furthermore adjustable with respect to the base 41 by means of the spindle and handle 44.

The whole grinding mechanisms can also be adjusted along the oscillatory shaft 21 by means of the gear-rack 45 on the shaft 21 and the gear 46 in the lever 30_a, controllable by the pin 47, the lever 36_a being provided with similar clamp-

ing means as indicated at 48 in Fig. 5, whereby the lever 36_a on the shaft 22 can be made to follow any movements of the lever 30_a on the shaft 21 when operated by the pin 47.

In Fig. 3, a fragmentary detail slightly enlarged illustration shows a simple and advantageous construction of the shaft 21.

A slightly modified form of control mechanisms is illustrated in Fig. 6. The lever 30_b is held in a rigid position by the link 49, so that the shaft 22 alone is free for oscillatory turning movements. This form is particularly suited for cam-shafts, of which a cross section is indicated at 50, the grinding wheel indicated at 37 eventually to be on the same type of grinding mechanisms as illustrated in Fig. 4, in Fig. 6 being merely indicated in dotted lines to illustrate a grinding of a cam opposite to the cam responsible for the movements of the control mechanisms of this type.

The arm 24_b is provided with a number of holes 51 by which a link 52 is adjustably and pivotally connected at 53 with one end, the opposite end of the link 52 being pivotally connected at 54 to an adjustable contact-arm 55.

A bracket 56 mounted on the bed or central portion 11 of the main structure embodies a pivot 57 on which the contact-arm is adjustably mounted for swinging movements, the bearing-blocks 58 and 59 being shiftably mounted in the contact-arm 55 controllable by the adjusting means 60 and 61.

Of course, this modified attachment can also be used for larger strokes than customarily exist on cam-shafts, a proper operation merely depending on a proper proportioning of the several levers, easily arranged by any mechanic.

Furthermore, such an attachment can be designed to function on oppositely disposed cams or cranks as well as on pairing cams and cranks, the tilting contact-arm 55 being readily used for oppositely disposed surfaces, while the arm 24_b is then just as easily applied to pairing surfaces, in the manner described above.

From the detail illustration of the shaft 21 it will be clear that the gear-rack 45 is mounted in the shaft 21, which in turn is turnably mounted on an inner shaft 63, a bearing sleeve 62 serving to assure a proper wearing of the bearing surface, making an exchange of wearing surfaces easy, the whole being held in place by the set rings 64, such arrangement, of course being provided on the opposite ends of the shaft 21.

Having thus described my invention, I claim:

1. In a grinder, an operating structure including supports by which a crank shaft can be rotated around its central axis, a control mechanism designed to follow the movements of a crank of the crank-shaft, operating shafts disposed alongside of said structure with their axes parallel to the first-named axis, the control-mechanism including means for imparting oscillatory rotating movements to the operating shafts, a grinding mechanism in operative connection with said operating shafts and thereby with said control mechanism, adjusting means on the control-mechanism for setting the control-mechanism on said operating shafts with respect to said crank-shaft, other adjusting means for holding the control-mechanism snugly to a crank of the shaft, other adjusting means on the grinding mechanism for setting the grinding mechanism on the operating shafts for co-operation with said control-mechanism, contact means on the grinding mechanism for contact-

ing with a crank of the shaft, further adjusting means for contacting the grinding mechanism with the crank, and still further adjusting means for the grinding mechanism transversely to the operating shafts, the grinding mechanism including an actuating and an actuated portion pivotally connected, and a balancing means for the grinding mechanism.

5 2. In a grinder, a contact-arm having a pivot-support at one end and means to contact with the side of a crank-pin at the opposite end, a grinder base designed to support a motor and a grinding wheel and having means to pivotally connect with the contact arm, and a counter-balance on the base for balancing the base with motor and grinding wheel on the arm.

10 3. In a grinder, a contact-arm having a pivot-support at one end and means to contact with the side of a crank-pin or cam at the opposite end, a grinder base designed to pivotally rest on the arm and having means for slidably supporting the grinder proper, the grinder proper being adjustable transversely to the axis of the pivot.

15 25 4. In a grinder, a control-mechanism for use on cam-shafts comprising a control-arm with a pivot-support at one end and actuated means at a distance from the pivot-support, the control-arm having various connections spaced differently from the pivot-support, a contact-arm having means at one end adjustably connected

to said connections, blocks slidably mounted in the contact-arm in pairs with the adjoining faces designed to engage a pivot-support, and adjusting means for the blocks for varying the oppositely disposed lever-ends with respect to said 5 adjoining faces.

5. In a grinder, a control-mechanism for use on crank-shafts comprising a control-arm with a pivot-support at one end and actuated means at a distance from the pivot-support for controlling the movements of the arm with respect to the pivot-support, the control-arm having contact means to slidably engage against the sides of a crank-pin at the opposite end with respect to the first-named end, and a clamping member 10 15 having contact-means to adjustably cooperate with the first-named contact means for holding the outermost end of the control-arm in contacting engagement with the crank-pin.

6. In a control mechanism for grinders of the 20 class described, a control-arm having a pivot support at one end and a contacting means at the opposite end designed to slidably engage against the sides of a part to be ground, the arm having an actuating pivot intermediate the 25 two ends, and a clamping member adjustably mounted on the second-named end and having contacting means to adjustably co-operate with the first-named contacting means.

30
ENGELEBERT MÜHLBACHER.
